UNITED STATES PATENT OFFICE

ALBERT H. TINNERMAN, OF CLEVELAND, OHIO

REVERSIBLE STOVE

Application filed January 26, 1929. Serial No. 335,328.

This invention relates in general to reversible stoves and while the invention is hereinafter more fully explained in connection with a gas stove, it will be manifest that other heating mediums may readily be employed, as, for example, electricity or oil.

A principal object of the present invention is the provision of a stove having the usual burner for open cooking and having also oven and broiler parts which may be installed at will as a right or left hand stove, or may have its parts separated and located in different parts of the same kitchen, all as particular conditions and space arrangement render desirable.

Another important object of the invention is the provision of a stove constructed of two divisible units as the burner box, as one unit, and the oven and broiler, as a second, which may be erected in desired right or left hand stove assembly without need of providing a fixed frame for the purpose and which on the other hand will merely require that the two parts be connected together in simple fashion and the whole supported upon legs attached directly to the exposed corners or ends of the assembly.

Another important object of the invention is the provision of means for providing heating medium, which will be easily adapted to all of the arrangements of which the construction is capable.

Numerous other objects and advantages of the invention will be apparent as it is better understood from the following description, which, taken in connection with the accompanying drawings, discloses a preferred embodiment thereof.

Referring to the drawings, Fig. 1 is a rear elevation of a stove made in accordance with my invention; Fig. 2 is a vertical longitudinal section taken through the stove adjacent the plane of connection between the burner box and oven box; Fig. 3 is a perspective view taken from the front of the stove and showing the parts as yet unconnected; Fig. 4 is a front elevation of a stove with the parts connected to make a left-hand stove; Fig. 5 is a front elevation showing the parts connected to make a right-hand stove;

Fig. 6 is a top plan view of a left-hand stove; and Fig. 7 is a top plan view of a right-hand stove.

For the purpose of illustrating my invention, I have shown on the drawing two separate stove parts indicated by reference characters 11 and 12. The part 11 is a combined oven and broiler part, which may have any usual or preferred construction, and the part 12 similarly is a burner box part having the usual open burners 13 and warming shelf 14. Each of these parts is complete in itself and is provided at its bottom with a relatively heavy band or reinforcing member 15. Each said part is constructed for attachment to a similar portion of the band of the companion part at each corner and to suitable stove legs or to suitable stove legs only.

This provision for the joining of the stove parts to each other or to the legs consists in two apertures 16 arranged on each face adjacent the corner. Stove legs are indicated at 17 of any usual or preferred construction, adapted however, for engagement with four openings 16 at a corner, two of such openings as has been mentioned being located at the meeting faces of the stove. Bolts 18, as indicated in Fig. 3, are provided to hold either the stove legs or the stove parts together when arranged through registered openings 16.

The parts are arranged in Fig. 3 to be assembled into a right hand oven stove. This is accomplished by bringing the two parts so that the exposed side faces of the part 11 is in contact with the hidden side face of the part 12. The bolts 18 are then arranged through the openings 16 which are then brought into alignment and thus screwed home. The legs are attached in the usual manner, the bolts extending through the opening 16 at the four corners of the resulting assemblage.

The stove may be reversed so that the burner box is the right of the oven part by removing all the bolts mentioned and bringing the exposed side face of the burner box up against the hidden side face of the oven part, bolts threaded through the aligned openings, then will permit of the tight as-

semblage of the unit in the opposite or reversed relation of its parts. Similarly then the legs may be positioned upon the exposed corners of the resulting assembly to support the stove in service.

5 It is thought unnecessary to fasten the adjacent stove sides to each other except at the bottom because the arrangement of the legs on the two parts at their outer sides 10 tends to bring the tops of the parts into tight engagement by gravity and the tension upon the bolts extending through the openings 16 is all that is needed to rigidly assemble the construction. Of course, other 15 and additional fastening means may be employed if desired.

Each one of these stove parts is so constructed therefore, as to permit of the arrangement of four legs for each part and 20 their separate erection in different parts of the same room or, for that matter, in different localities entirely, merely by attaching four supports to the corner of the particular 25 stove part in the manner already described for attaching them at two corners.

The stove shown in the drawings of this application employs gas as a heating medium. To permit satisfactory connection of the gas conduits on the burner box and oven 30 when they are connected together as a unit, I have shown the burner box as having two conduits 20 and 21 which extend across the box from the rear to the front thereof and are connected together at the front by a 35 manifold 22. Where the top is connected for a left-hand stove, the conduit 20 is connected to the supply line and the conduit 21 is connected to a manifold 23 at the rear of the oven. The oven manifold extends across 40 the back of the oven and when connected at one end of the pipe 21, has the other end closed by a cap 24. When the connections are made for a right-hand stove, the pipe 21 is connected to the supply line while the pipe 45 20 is connected to the oven manifold.

The connection for the oven thermostat extends beyond the back of the oven near the base thereof and is provided with a sprocket wheel 25 which is connected by a 50 chain 26 to another sprocket wheel 27 in the case of a right-hand stove. This wheel is attached to the stem of a valve 28 which is connected in the manifold between the oven outlet and the source of supply. In 55 case of a left-hand stove, the chain is passed over a wheel 29 which is attached to a stem of valve 30. It is desirable to have a valve on each side of the gas outlet to insure positive control of the gas under the action of 60 the thermostat. By virtue of the gas connections, my invention is applicable for enabling the burner box to be supported independently of the oven and that a plurality of burner boxes may be connected together 65 to a common oven in cases where additional

cooking space is desired. A further advantage of my invention is the fact that the burner box and oven may be readily connected together in an expeditious manner without the necessity for a rigid base which 70 is attached to the supporting legs.

I claim:

1. A stove comprising a combined oven part and a burner box part adapted to be reversibly arranged in adjacent relationship, 75 each of said parts being provided with a heating medium supply means, and one of the parts including a conduit having two valves, a gas supply control member and means for selectively connecting the member 80 to either of said valves.

2. A stove comprising a plurality of box-like parts, having burners therein and adapted to be reversibly arranged in adjacent relationship, each of said parts being provided with a heating medium supply means, one of said parts including a conduit having two valves, a gas supply control member located adjacent the vertical mid portion of one of the parts, and means for operatively 90 connecting the member to either of said valves.

3. A stove, comprising a combined oven part and a burner box part adapted to be arranged in adjacent relationship, each of 95 said parts being provided with a heating medium supply means, the supply means on the oven part including a conduit extending across the part and at the rear thereof, and the supply means on the burner box including a conduit extending across the part and at the front thereof, said parts being adapted to be interconnected by a conduit extending from the front to the rear of the stove, the oven part conduit having a valve disposed therein, a gas supply control member positioned adjacent the mid-portion of the oven part, and operating means for connecting the member with said valve.

In testimony whereof, I hereunto affix my 110 signature.

ALBERT H. TINNERMAN.
